(57) **CLAIM**

The ornamental design for a supportive pillow, as shown and as described.

DESCRIPTION

FIG. 1 is a left side perspective view of a supportive pillow showing my new design;

FIG. 2 is a top view thereof;

FIG. 3 is a bottom view thereof;

FIG. 4 is a left side view thereof;

FIG. 5 is a right side view thereof;

FIG. 6 is a back view thereof; and,

FIG. 7 is a front view thereof; and,

FIG. 8 is another left side perspective view of the supportive pillow in accordance with my new design shown with a person's head laying on the supportive pillow.

The broken lines included in FIG. 8 of the supportive pillow illustrate environmental structure and form no part of the claimed design. The remainder of the broken lines shown in the figures represent portions of the supportive pillow that form no part of the claimed design.

Further, the stipple shading shown in the figures is used to represent three-dimensional form and not surface ornamentation.
